UNITED STATES PATENT OFFICE.

LILLIAN M. KEEZER AND FRED A. OSGOOD, OF BOSTON, MASSACHUSETTS; SAID OSGOOD ASSIGNOR TO SAID KEEZER.

KNIFE SHARPENER.

Application filed March 30, 1926. Serial No. 98,576.

This invention relates to an improved device for sharpening knives.

The object of the invention is to provide a simple, durable and cheap device for sharpening knives, and to this end the invention comprises a knife sharpener embodying a holder with a pair of sharpener members mounted thereon with abrading surfaces oppositely disposed to each other and lying in planes which intersect adjacent their lower edges, the lower edges being notched, or having notches therein in staggered relation to each other.

The invention consists in the improved knife sharpener and in the sharpener member of said knife sharpener as set forth in the following specification and particularly pointed out in the claims.

Referring to the drawings:—

Figure 1 is a plan view of an embodiment of one form of our invention.

Fig. 2 is a front elevation of the same.

Fig. 3 is a transverse section taken on the line 3—3, Figure 1.

Fig. 4 is a perspective view of a sharpener member.

Fig. 5 is a transverse section similar to Fig. 3 but illustrating a modified form of sharpener members.

Like numerals refer to like parts throughout the several views of the drawings.

In the drawings, referring to Figures 1 to 4 inclusive, 5 is the holder for the sharpener members. This holder is preferably constructed of wood in two parts 6 and 7 joined together in any suitable manner as by dowels 8. The parts 6 and 7 are preferably convexly curved upon their upper ends and are provided with slots 9 and 10 respectively in which are detachably positioned sharpener members 11 and 12.

These sharpener members are triangular in cross section, as illustrated in Figure 4 and have their three faces provided with abrading surfaces and with their edges provided with notches 13. When positioned in their respective slots 9 and 10 the sharpener members are clamped in the holder by screws 14, an abrading surface on one of the sharpener members being oppositely disposed to the abrading surface on the other sharpener member, and the slots 9 and 10 are so positioned and related to each other that when the sharpener members are in-

serted therein their adjacent abrading surfaces will be positioned at an acute angle and the planes of said abrading surfaces will intersect each other adjacent the lower edges of the sharpener members, that portion of the lower edge of the sharpener members which is located between notches therein, projecting into the notches of the member opposite thereto, that is, the notches are located in staggered relation to each other on the two sharpener members, and the portions between the notches on one member project into the notches on the other member.

In using the device the holder is screwed to a suitable support 19 as illustrated in Figs. 2 and 3, and the knife is placed with its edge between the adjacent surfaces of the sharpener member as illustrated in dotted lines, Fig. 3, and when being sharpened is drawn toward the user, then lifted up, moved backwardly and inserted again between the sharpener members and again drawn forward until the necessary sharpness has been imparted to the edge of the knife.

In Fig. 5 a modified form of our invention is illustrated which differs from the form illustrated in Figures 1 to 4 inclusive only in the shape of the sharpener members.

Referring to Fig. 5, 5' is the holder and 15 and 16 the sharpener members. These sharpener members operate in the same manner as hereinbefore described in that embodiment of our invention illustrated in Figs. 1 to 4 inclusive, but differ therefrom in shape 90 in that they are rectangular in cross section, whereas the sharpener members illustrated in said Figs. 1 to 4 inclusive are triangular in cross section. The sharpener members 15 and 16 are each provided with abrading surfaces on the opposite faces thereof and are provided with notches 17 and 18 in their edges which are for the same purpose as the notches 13 in the other form of our invention.

The operation of sharpening the knife is exactly the same as hereinbefore described in relation to the other form of our knife sharpener.

It will be seen by the construction hereinbefore set forth that either form of the knife sharpeners illustrated may be withdrawn from its slot in the holder and reversed, end

for end, or turned laterally so as to bring all abrading surfaces into use and all edges of the sharpener members into use.

We claim:

5. 1. A knife sharpener having, in combination, a holder, a pair of triangular sharpener members each provided with a plurality of abrading surfaces detachably mounted upon said holder, with an abrading surface on one member oppositely disposed to an abrading surface on the other member and with said oppositely disposed abrading surfaces lying in planes which intersect each other at an acute angle adjacent their lower edges, said lower edges having notches therein in staggered relation to each other.
10. 2. A knife sharpener having, in combination, a holder, a pair of triangular sharpener members each provided with a plurality of abrading surfaces rigidly and detachably mounted upon said holder, with an abrading surface on one member oppositely disposed to an abrading surface on the other member and with said oppositely disposed abrading surfaces lying in planes which intersect each other at an acute angle adjacent their lower edges, said lower edges having notches therein in staggered relation to each other, the portion between the notches on the edge of one sharpener member projecting into the notches on the edge of the other sharpener member.
15. 3. A knife sharpener having, in combination, a holder, a pair of sharpener members with abrading surfaces rigidly and detachably mounted in slots provided in said holder, with said abrading surfaces oppositely disposed to each other and with the abrading surfaces of said sharpener members lying in planes which intersect each other at an acute angle adjacent their lower edges, said lower edges having notches therein in staggered relation to each other, and

means to clamp said sharpener members in said slots.

45

4. A knife sharpener having, in combination, a holder, a pair of triangular sharpener members with abrading surfaces detachably and reversably mounted in slots provided in said holder, with said abrading surfaces oppositely disposed to each other and with the abrading surfaces of said sharpener members lying in planes which intersect each other at an acute angle adjacent their lower edges, said lower edges having notches therein in staggered relation to each other, and means to clamp said sharpener members in said slots.

50

5. A knife sharpener having, in combination, a holder, a pair of sharpener members polygonal in cross section, with abrading surfaces on a plurality of faces and detachably and reversibly mounted in slots provided in said holder, with an abrading surface on one member oppositely disposed to an abrading surface on the other member, said abrading surfaces lying in planes which intersect each other at an acute angle adjacent their lower edges, said lower edges having notches therein in staggered relation to each other.

60

6. A sharpener member for a knife sharpening device, the same being polygonal in cross section with abrading surfaces on a plurality of its faces and with notches provided in the edges thereof.

65

7. A sharpener member for a knife sharpening device, the same being triangular in cross section with abrading surfaces on a plurality of its faces and with notches provided in the edges thereof.

70

In testimony whereof we have hereunto set our hands.

LILLIAN M. KEEZER.
FRED A. OSGOOD.
